SHOE WITH SHEATH FORM OF UPPER

David E. Levin, Brooklyn, N. Y., assignor to I. Miller & Sons, Inc., Long Island City, N. Y., a corporation of New York

Application November 6, 1947, Serial No. 784,441

4 Claims. (Cl. 36—11)

1

My present invention relates to shoes and a method of making them.

The primary object of this invention is to provide a shoe upper which is of such construction as to effect several advantages among which are improved comfort and appearance and simplicity of manufacture.

The above and other objects, features and advantages will be fully understood from the following description considered in connection with the accompanying drawings which are to be considered as illustrative of my invention but not in limitation thereof.

In the drawings:

Fig. 1 is a perspective view of a shoe embodying the present invention;

Fig. 2 is a plan view of an upper blank of this invention;

Fig. 3 is a plan view of the upper in an intermediate stage of the manufacture thereof;

Fig. 4 is a sectional view on the line 4—4 of Fig. 3;

Fig. 5 is a sectional view on the line 5—5 of Fig. 1;

Figs. 6 and 7 are sectional views similar to Fig. 5, showing two different modifications;

Fig. 8 is a side view of the forward part of the shoe shown in Fig. 1.

Briefly described, the shoe of the present invention comprises an upper in the form of a sheath of any suitable shape and of any desired character as to details of ornamentation or absence of the latter. The sheath may be lined or unlined and may be formed of any of the numerous materials which are suitable for shoe uppers, including leather, fabric, plastics, etc. The upper is formed from a blank cut to a predetermined peripheral edge contour to provide a sheath of the desired shape, said blank having a part which forms an element of the shoe bottom and a part which forms the vamp or forepart of the shoe upper. Further, in accordance with the preferred embodiment of this invention, provision is made for conforming the sheath to the curvature of the longitudinal arch at the inner side of the wearer's foot.

Referring now to the drawings in detail, the shoe shown in perspective in Fig. 1 as the shoe for the right foot comprises an upper 10 which is in the form of a sheath and includes a vamp or forepart 12 and a bottom part 14 which is continuous with part 12 and is an element of the shoe bottom. The latter includes an outsole 16 and a wedge heel 18, it being understood that any suitable heel may be used instead of a

2

wedge heel. It will be observed that bottom 14 of the sheath extends transversely from one longitudinal side edge of the shoe to the opposite longitudinal side edge. Said upper 10 also includes a portion 20 which conforms to the curvature of the arch of the foot as will be herein-after described in further detail. As shown in Fig. 1, the bottom 14 of the upper or foot sheath 10 extends for the full length of the shoe, although this is subject to modification, within the scope of the invention, and the vamp extends from the toe to substantially the ball line at the outer side edge of the shoe. The bottom part 14 of the foot sheath 10 is secured to the heel and to the outsole in any suitable way, preferably as here shown by an adhesive interposed between said heel, outsole and bottom part 14 of the sheath throughout the respective contiguous areas thereof.

20 The construction of the upper or foot sheath 10 will now be further described with particular reference to the upper blank 10A shown in Fig. 2, for the outer layer 21 of the sheath. When, as shown in Figs. 1 to 5 the upper includes a lining 23, a blank of lining leather or other suitable material is provided, said lining blank being of the same size and shape as the upper blank 10A. Said lining blank is shown in section at 10B in Fig. 4. Blank 10A is provided with a narrow longitudinal cut-out in the shank portion of the bottom forming part 14 of the blank and the side edges 24 and 26 are brought together and stitched together as indicated at 28 in Figs. 1 and 3. When the upper is lined, the blank 10B is provided with a similar cut-out and the side edges of the latter are stitched together as indicated at 30 in Fig. 4. The cut-out portion 22 and the stitching thereof at 28 results in conforming the arch portion 20 of the upper to the arch of the foot, and the lining is similarly conformed. It will be understood that the cutout in the lining is of the same size and shape and is located in the same position in the lining blank as the cut-out 22 of blank 10A; accordingly blank 10A may also be considered as illustrative of the lining blank 10B, so as to avoid duplication of illustration.

An insole or interliner 32 shown in dotted peripheral edge outline in Fig. 3 is provided in 50 the bottom of the sheath 10 in accordance with the preferred embodiment of the invention, although as indicated in Fig. 6, the omission of the insole or interliner is within the scope of this invention. When the interliner 32 is used it is preferably formed of insole leather, but it can be

formed of any other suitable material and it is preferably of full shoe length and width.

In forming the sheath or upper 10 from the blanks 10A and 10B, after the cutouts are seamed as indicated at 28 and 30, the insole or interliner 32 is placed between the two blanks at the bottom forming parts thereof and said blanks and insole are adhesively united to each other throughout their respective contiguous areas. Thus, as shown in Figs. 3 and 4, the parts of the blanks which form the vamp 12, including the longitudinal arch portion 20 are adhesively secured directly to each other, while the bottom forming parts of the blanks are adhesively secured to the opposite surfaces, respectively, of the insole or interliner 32 throughout said surfaces. After the parts are thus assembled and united to produce the step product shown in Fig. 3, the vamp forming part 12 is folded over the bottom forming part 14 and the two parts are then secured together at their edges preferably by stitching as indicated at 34. As shown in Figs. 1 and 8, stitching 34 extends from a point 36 corresponding to point 36a of Fig. 3, near the toe, at one side of the shoe, then around the toe to a point 38 at the opposite side of the shoe. Referring to Fig. 3, the points 36a and 38b are the terminals of the edge 40 of the vamp forming part 12 which is stitched to the edge of the bottom forming part. Preferably, the stitching is continued completely around the sheath 10 at the edge thereof as indicated at 40, this being desirable especially when the upper is provided with a lining.

In Figs. 1, 5 and 8, the stitched edge portions of the vamp and bottom are in aligned relation, but it will be understood that said edge portions may be secured adhesively or otherwise in overlapped relation as shown, for example, at 34a in Fig. 7. Further, it will be observed that the upper 10 need not have a lining and the bottom part 14 of the sheath need not have an insole or interliner, the construction of the upper being otherwise the same as indicated in Fig. 6. Moreover, it will be understood that the inner sole or interliner 32 may be omitted from the lined upper shown in Figs. 1 to 5 and that in such case, the outer layer and the lining may be adhesively secured in surface-to-surface relation throughout their co-extensive areas.

After the foot sheath is formed as hereinbefore described, a last is inserted and while the sheath is on the last the outsole and heel are attached. It will be understood that the sheath is formed from a blank which is cut to the shape and size required to produce a sheath which will fit properly on the last substantially as in the manufacture of slip lasted shoes. It is to be noted, however, that it is within the scope of this invention to apply the upper to the last before the outer edges of the vamp and bottom of the upper are secured to each other, particularly in a construction such as that illustrated in Fig. 7, wherein the secured outer edges of the vamp and bottom are disposed in overlapping relation.

Any suitable means may be provided at the rear part of the shoe for holding the shoe on the wearer's foot. As shown in Fig. 1, such means may comprise a buckled ankle strap 42, of a well-known type, having its ends secured beneath the bottom 14 of the foot sheath 10 as indicated at 44, 46.

The invention is shown embodied in a lady's shoe but it is obvious that men's and children's shoes may be similarly constructed, and that

various styles of shoes may be made according to this invention. It will be readily appreciated also that the part 12 of the sheath need not be closed as shown but may have an open toe, for example, or other openings or open portions therein, and may be of various other types as will be readily apparent to shoe artisans, in view of the present disclosure. Finally, it will be understood that various changes in the details of construction and in the arrangement of parts may be made without departing from the underlying idea or principles of my present invention within the scope of the appended claims.

Having thus described my invention, what I claim and desire to secure by Letters Patent is:

1. In a shoe having an outsole, an upper having a vamp which includes a portion shaped to conform to the longitudinal arch of the foot and a bottom part disposed over and attached to said outsole as an element of the shoe bottom, said bottom part being integral with the forward portion of said vamp and said portion of the upper at the longitudinal arch side of the shoe and extending to the opposite side of the shoe, said vamp and said bottom part having adjacent edge portions secured in position at said last mentioned side of the shoe, said vamp and said portion of the upper terminating in a rear edge which extends forwardly from a point located in the rear part of the shoe at said first mentioned side thereof to a point located in the forward part of the shoe at said opposite side thereof.

2. In a shoe having an outside, an upper having a vamp which includes a portion shaped to conform to the longitudinal arch of the foot and a bottom part disposed over and attached to said outsole as an element of the shoe bottom, said bottom part being integral with the forward portion of said vamp and said portion of the upper at the longitudinal arch side of the shoe and extending to the opposite side of the shoe, said vamp being integral with said portion of the upper and being in one integral piece extending continuously from one side of the shoe to the other, said vamp and said bottom part having adjacent edge portions secured in position at said last mentioned side of the shoe, said upper having an outer layer and a lining, and an inner sole disposed in said bottom part of the upper between said layer and said lining, said vamp and said portion of the upper terminating in a rear edge which extends forwardly from a point located in the rear part of the shoe at said first mentioned side thereof to a point located in the forward part of the shoe at said opposite side thereof.

3. In a shoe having an outsole, an upper having a vamp which includes a portion shaped to conform to the longitudinal arch of the foot and a bottom part disposed over and attached to said outsole as an element of the shoe bottom, said bottom part being integral with the forward portion of said vamp and said portion of the upper at the longitudinal arch side of the shoe and extending to the opposite side of the shoe, said vamp and said bottom part having adjacent edge portions secured in position at said last mentioned side of the shoe, said vamp and said portion of the upper terminating in a rear edge which extends forwardly from a point located in the rear part of the shoe at said first mentioned side thereof to a point located in the forward part of the shoe at said opposite side thereof, said bottom part of the upper being substantially co-extensive with said outsole.

4. In a shoe having an outsole, an upper having a vamp which includes a portion shaped to conform to the longitudinal arch of the foot and a bottom part disposed over and attached to said outsole as an element of the shoe bottom, said bottom part being integral with the forward portion of said vamp and said portion of the upper at the longitudinal arch side of the shoe and extending to the opposite side of the shoe, said vamp being integral with said portion of the upper and being in one integral piece extending continuously from one side of the shoe to the other, said vamp and said bottom part having adjacent edge portions secured in position at said last mentioned side of the shoe, said vamp and said portion of the upper terminating in a rear edge which extends forwardly from a point

located in the rear part of the shoe at said first mentioned side thereof to a point located in the forward part of the shoe at said opposite side thereof.
